UNITED STATES PATENT OFFICE.

ROBERT ELLISTON CARLTON, OF LATONIA, KENTUCKY, AND MARCUS WARLAND RYLE,
OF BALMORHEA, TEXAS.

SAFETY DEVICE FOR RAILWAY-TRACKS.

985,006.

Specification of Letters Patent. Patented Feb. 21, 1911.

Application filed May 4, 1910. Serial No. 559,373.

To all whom it may concern:

Be it known that we, ROBERT E. CARLTON, a citizen of the United States, and a resident of Latonia, in the county of Kenton and State of Kentucky, and MARCUS W. RYLE, a citizen of the United States, and resident of Balmorhea, in the county of Reeves and State of Texas, have invented certain new and useful Improvements in 10 Safety Devices for Railway-Tracks, of which the following is a specification.

Our invention relates to improvements in guard rails for preventing the derailing of cars on railway tracks, and it consists in 15 the combinations, and constructions and arrangements of parts herein described and claimed.

An object of our invention is to provide a device which may be advantageously used 20 at points at which there is danger of derailing, such as on curves, or upon bridges, or other structures, where derailing would lead to the most serious consequences.

A further object of our invention is to 25 provide electrical means for notifying the operator if the derailing should occur and at what point.

A further object of our invention is to 30 provide a novel form of guard rail for preventing the derailing of the train and serving to effect the reentrance of the wheels upon their proper rails if such derailing should occur. This is accomplished by 35 means of grooves made in the rails in such a manner that the flanges of the wheels are guided by the grooves so that the wheels themselves are turned back upon the main track.

Further objects and advantages will appear in the following specification and the 40 novel features of the device will be particularly pointed out in the appended claims.

Our invention is illustrated in the accompanying drawings, in which:

Figure 1 is a plan view of the track provided with our invention. Fig. 2 is a side view of a portion of the track showing the spring for actuating the switch tongue. 50 Fig. 3 is a section along the line 3—3 of Fig. 1, Fig. 4 is a section along the line 4—4 of Fig. 1, and Fig. 5 is an enlarged section along the line 5—5 of Fig. 1.

In Fig. 1 we have shown a track comprising the ties 1 and the main rails 2 and 3. In

a section of track, at points where derailing is liable to occur, such as on curves, we remove the rails of the main track and insert in place thereof the rails shown in Fig. 1. In this figure it will be seen that 60 there is an outer rail 4 of a curved shape which is placed between the sections of the main rail 2, being secured to the ties 1 in the ordinary manner. Inside of the outer rail 4 is a rail 5 which is in line with the 65 main track rails 2—2 and which is provided with pivoted switch tongues 6 and 7 at the ends thereof. This rail is provided with a series of diagonal grooves 8. Within the rail 5 is a third rail or inner guard rail 9 70 having a curved form as indicated in the figure, the curve of the rail being opposite to that of the outer guard rail 4. The inner guard rail 9 is also provided with a series of diagonal grooves 10. Between the track 75 rail 5 and the outer rail 4 is a steel or iron spacing plate 11, while a similar spacing plate 12 is placed between the rail 5 and the inner guard rail 9.

The opposite side of the track is similarly provided with an outer guard rail 13, and the inner track rail 14 which has diagonal grooves 14^a. A third rail 15 is provided which is similar to the rail 9 and is provided with grooves 16. The rail 14 is 85 provided with the switch tongues 17 and 18 similar to the switch tongues 6 and 7.

On the outer side of each of the rails 4 and 13 are secured springs 19. Each of these springs is connected by a rod 20, which 90 passes through the opening in the outer guard rails, with its respective switch tongue, as plainly shown in the drawing. These springs tend to hold the switch tongues against the outer guard rails so as 95 to form a continuous section of track between the main track sections 2—2 and 3—3. The rail sections are joined together by means of the fish-plates 21 and the rails are secured to the ties in the ordinary manner.

From the foregoing description of the various parts of the device, the operation thereof may be readily understood.

Ordinarily as a train passes a section of 105 track provided with our invention, the wheels on one side of the train follow the track 2, 5, 2, since as before stated, the switch tongues 6 and 7 are normally held by their springs so as to form a continuous 110

track. The wheels on the opposite side of the train would follow the rail sections 3—14—3. Now, if one of the wheels should jump the track the inner or outer guard rails 5 would prevent the train from complete derailment. Moreover, as the train proceeds, the flanges of the wheels will engage the diagonal grooves, thereby tending to force the wheels back upon the track. The grooves 10 are shown as inclined in opposite directions, so that if the train is proceeding in one direction, as for instance, from left to right, in Fig. 1 the flanges on the wheels on the left hand side of the train will engage the grooves 8 and tend to force the wheels back upon the track. If the derailment is still 15 farther to the left, the grooves of the rail 15 will engage the flanges of the wheels of the right hand side of the train and tend to force the wheels back upon the track. Conversely, if the derailment should be in the 20 opposite direction, the grooves 14^a of the rail 14 and grooves 10 of the rail 9 would come into play. If the grooves should fail to engage the flanges the curvature of the inner and 25 outer guard rails would themselves tend to force the wheels back again upon the track. In order to permit the flanges of the wheels to be guided to their proper places, we provide the spring tongues 6, 7 and 17, 18. As 30 soon as the flanges, which engage one of the outer guard rails, reach the spring tongue, they push it aside, and the tongue may spring back into its position, thus leaving 35 the apparatus in normal condition.

We are aware that other forms of the device based upon the same idea might be made, but we consider as our own all such modifications as fairly fall within the spirit 40 and scope of the invention.

We claim:

1. A safety device for railways comprising an outer guard rail on each side of the track, joining the main rails, an inner guard

45 rail on each side of the track spaced from said outer guard rail, and an intermediate main track section provided with spring-controlled switch tongues normally in engagement with said outer guard rails.

2. A safety device for railways comprising 50 an outwardly curved outer guard rail on each side of the track joining the main rails, an inwardly curved inner guard rail on each side of the track spaced from said outer guard rail, and an intermediate main track 55 section provided with spring-controlled switch tongues, at each end thereof, normally in engagement with said outer guard rails.

3. A safety device for railways comprising 60 an outer guard rail on each side of the track, an inner guard rail on each side of the track provided with diagonal grooves, and a central track rail between said outer and inner guard rails provided with diagonal 65 grooves inclined in an opposite direction from said first mentioned grooves, and spring controlled switch tongues at each end of said central track rails.

4. A safety device for railways comprising 70 an outer guard rail on each side of the track, an inner guard rail on each side of the track, a central track rail between said outer and inner guard rails, pivoted switch tongues at the ends of said central section, 75 springs secured to said outer guard rails for holding said switch tongues normally in engagement with said outer guard rails.
